COMBINED WINDOW JAMB ANCHOR AND ADJUSTER

Edmund Peremi, Bayside, N. Y., assignor, by mesne assignments, to General Bronze Corporation, Garden City, N. Y., a corporation of New York

Application May 20, 1947, Serial No. 749,243

4 Claims. (Cl. 189—73)

1

This invention is particularly adapted for use with a light metallic window and door frame.

In the use of light metallic window or door frames, particularly those constructed of extruded aluminum, it has been found that the jambs and headers sometimes become distorted. Particularly the vertical jambs become distorted by bowing outwardly between the header and the sill, the degree of outward bowing varying, in many cases, with the length of the jambs.

It is an object of this invention to provide an anchor for the vertical jambs of such a window or door frame with which is combined an adjuster which may be used to overcome the distortion of the jambs and to maintain them in proper rectilinear form for cooperative coaction with the sashes and their accessories.

A further object resides in the provision of such a device which is so constructed that it may be adjusted to compensate for reasonable distance variations between the masonry and the frame.

It is a further object of the invention to so construct the adjuster that relatively small adjustments which might be referred to as micrometer adjustments of the vertical jambs of the frame may be accomplished and, when accomplished, maintained.

It is another object of the invention to provide a device of the above referred to character which is adjustable longitudinally of the frame member to properly secure the frame to the masonry and to apply compensating force at the point where such force is needed and without the use of wedges such as are customarily used.

With these and other objects in view, which will appear as the description of this invention progresses, the invention resides in the combination and arrangement of parts illustrated in the drawing, described in the specification and recited in the claims, the particular forms of the several elements of the invention illustrated in the drawing being selected for the purpose of exposing the invention, its application and its functioning.

In the drawing:

Figure 1 is a horizontal sectional view on the line 1—1 of Figure 3 through a portion of a vertical jamb of a metallic window frame, showing a portion of the sill and in dotted lines indicating the building framing;

Figure 2 is a vertical sectional view taken on the line 2—2 of Figure 1, looking in the direction of the arrows; and

Figure 3 is an elevation looking at one face of the anchor and adjuster.

Referring to the drawing, the building window-opening frame 10 or masonry is indicated in dotted lines in Figure 1. This framing may be, of course, of masonry or wood or masonry with wood inserts.

2

One of the vertical jambs 11 of the window framing, which is formed preferably of metal such as extruded aluminum, is illustrated as being provided with flanges 12 such as are now quite commonly used, which flanges are in spaced relation to each other, forming a vertical recess 13 in the jamb.

In Figure 1 the vertical jamb is shown in association with a sill 14 and sashes 15 and 16 which operate in the usual grooves 17 in the jambs.

The anchor and adjuster includes an anchor plate 18 which is adapted to be secured in the manner in which anchors are usually secured to the building window-opening frame or masonry 10 by suitable means such as a fastener 19.

This anchor plate is provided with a substantially flat body portion 18' and this body portion is provided at one edge with a pair of spaced ears 20 and between these ears 20 the anchor plate is provided with an ear 21 which is offset from the plane of the ears 20, as illustrated in Figures 1 and 3 of the drawing. At the opposite side of the anchor plate 18 an ear 22 is provided, which ear is offset from the plane of the adjacent portion of the anchor plate 18 to cooperate with the portion 23 of said plate in a manner similar to that in which the ears 20 and 21 cooperate.

In applying this anchor plate to the window frame the plate is canted upwardly or downwardly to locate the ears 21 and 22 behind the flanges 12 of the vertical jamb of the window frame, and then is moved to a position substantially normal to the vertical plane of the window frame to engage the ears behind the flanges 12 and to engage the flanges 12 between the ears 20 and 21 and between the ear 20 and the portion 23 of the anchor plate, the distance between the ears 20 and 21 and between the ear 20 and the portion 23 of the anchor plate being normally sufficiently less than the thickness of the flanges 12 to permit a tight frictional engagement between the anchor plate and the flanges 12 of the jamb when the anchor plate is moved to its final working position.

An adjuster is mounted on the anchor plate. This adjuster includes a bearing head 24 which is provided at its edge with means to receive an adjusting tool, such means being illustrated in the drawing as a plurality of notches 25, and is provided with a bearing portion 26 that is adapted to engage the building window framing 10.

An adjusting screw 27 is rigidly associated with the head 24 and has screw-threaded engagement with the anchor plate 18 at 28.

After the anchor plate 18 has been secured in place as heretofore described, the adjuster may be actuated to align the vertical jamb of the window frame to relieve it of any outward bowing that it possesses. This adjustment is accom-

plished by rotating the adjuster until it is based against the building window framing and then continuing the rotation of the screw until the vertical jamb has been forced inwardly between its ends where they join the sill and the header to a sufficient degree to overcome any vertical distortion that the jamb possesses.

This rotation of the screw may be accomplished by means of a suitable tool, such as a screw driver, that may be inserted between the window frame and the adjacent face of the building window-opening framing and engaged with the adjacent notch 25 in the head 24, and thereafter used to turn the head to cause it to bear against the building window framing, and using this as a base to force the vertical jamb inwardly to overcome its distortion.

It will be realized that because of the screw-threaded engagement between the anchor plates 18 and the adjuster, a very fine adjustment of the vertical jamb of the window frame may be accomplished, which fineness of adjustment may be determined by the pitch of the screw threads.

Thus it will be seen that the invention contemplates a combined anchor and jamb adjuster, by means of which the frame may be anchored in the window opening and adjusted to overcome any distortion, such as oftentimes occurs in a light metallic window frame such as an extruded metal frame. Moreover, it is to be understood that the use of this combined anchor and adjuster is not confined to the vertical jambs because it may be used in connection with, and in cooperation with, the header, as well as the sill, if such use be found necessary or desirable. All of these elements will be referred to herein as frame members. It is to be understood, therefore, that the illustration and description of the invention in conjunction with the vertical jamb of a light metallic window frame is only for the purpose of disclosing an application of the invention.

Moreover, the use of these adjusters on opposite sides of the frame, makes it possible to center the frame both vertically and horizontally and to maintain it in its centered position without the use of wedges such as are now commonly employed.

Additionally, the fact that the adjusters, when arranged on opposite sides of the frame, are independently operable makes it possible to take up any reasonable amount of variation between the window or door frame member and the framing of the building opening, and when the window or door frame has been centered and its members properly aligned the frame will be securely held in position even without the use of attaching screws such as 19 because the force exerted by the adjusters against the plates 18 will firmly secure these plates to the window or door frame.

While a particular form of the invention has been illustrated and described, it is to be understood that the invention is not limited to this particular form because many changes in the details of construction may be made as the art will readily understand, and therefore the invention is to be limited only in so far as limitation is made necessary by the claims.

What is claimed is:

1. In combination, an anchor and adjuster for a metallic window frame having a substantially flat body portion, a pair of spaced ears arranged at one edge of said body portion and substantially in the plane thereof, an intermediate ear arranged at said edge between the first mentioned ears and spaced therefrom and offset from the

plane of said first mentioned ears, an additional ear arranged at the opposite edge of the body portion and offset from the plane thereof, an extension of lesser width than said body portion projecting therefrom adjacent to said last mentioned ear and having a portion offset from the plane of said body portion and in a plane substantially parallel with the plane of said body portion, and an adjusting screw mounted in said body portion and extending substantially normal thereto.

2. An anchor for a metallic window frame having a substantially flat body portion, a pair of spaced ears arranged at one edge of said body portion substantially in the plane thereof, an intermediate ear arranged at said edge between the first mentioned ears and spaced therefrom and offset from the plane of said first mentioned ears, an additional ear arranged at the opposite edge of the body portion and offset from the plane thereof, and an extension of lesser width than said body portion projecting therefrom adjacent to said last mentioned ear and having a portion offset from the plane of said body portion and in a plane substantially parallel with the plane of said body portion.

3. In combination, an anchor and an adjuster for a metallic window frame, having a substantially flat body portion, a plurality of ears at one edge thereof, certain of said ears being offset with respect to said body portion and other of said ears, an additional ear at the opposite edge of said body portion offset with respect to said body portion, an extension projecting from said last mentioned edge adjacent said last mentioned ear and having a portion offset with respect to said body portion and in a plane substantially parallel with the plane of said body portion, and an adjusting screw mounted in said body portion and extending substantially normal thereto.

4. An anchor for a metallic window frame, having a substantially flat body portion, a plurality of ears at one edge thereof, certain of said ears being offset with respect to said body portion and other of said ears, an additional ear at the opposite edge of said body portion offset with respect to said body portion, and an extension projecting from said last mentioned edge adjacent said last mentioned ear and having a portion offset with respect to said body portion and in a plane substantially parallel with the plane of said body portion.
